UNITED STATES PATENT OFFICE

HENRY CREMER, OF SOUTH GATE, CALIFORNIA

DESIGN FOR A VIOLIN BODY OR SIMILAR ARTICLE

Application filed November 24, 1930. Serial No. 37,769. Term of patent 14 years.

To all whom it may concern:

Be it known that I, HENRY CREMER, a citizen of the United States, residing in South Gate, in the county of Los Angeles and State of California, have invented a new, original, and ornamental Design for Violin Body or Similar Article, of which the following is a specification, reference being had to the accompanying drawing, forming part thereof.

I claim:

The ornamental design for a violin body or similar article, as shown.

In testimony whereof I have signed my name to this specification.

HENRY CREMER.
